UNITED STATES PATENT OFFICE.

DAVID LEVINSON, OF NEW YORK, N. Y.

TOY.

1,425,107.

Specification of Letters Patent. Patented Aug. 8, 1922.

Application filed March 30, 1921. Serial No. 456,863.

To all whom it may concern:

Be it known that I, DAVID LEVINSON, a citizen of the United States, and resident of the city of New York, in the county of New York and State of New York, have invented certain new and useful Improvements in Toys, of which the following is a specification.

The present invention relates to improvements in toys, and more particularly to toy building blocks for children's play.

One of the objects of the invention is to produce a group of blocks, which, when set up, constitutes a toy with which a game of chance may be played.

Another object of the invention is to provide one of the elements of the group, and more particularly the one which in setting up the toy completes the same, with a simple and efficient means for locking the members together.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:—

Figure 1 is a perspective view of the toy in its completed state; Figs. 2 to 7, inclusive, are perspective views of the several elements or building blocks, of which the toy is formed; and Figs. 8 to 11, inclusive, are perspective views of the building blocks in the several stages of setting up to form the toy illustrated in Fig. 1 of the drawings.

The set of building blocks, of which the toy is to be formed, comprises six quadrangular prisms, denoted by the numerals 10, 11, 12, 13, 14 and 15, all of which are of the same height and of the same transverse cross-section, the base of each being constituted by a square. These elements are to be set up and interlocked to form a spinning top, and may be divided into three pairs, the elements of each pair being placed

side by side, as appears from Fig. 1 of the drawings and the elements of any pair extending at right angles to those of the other pairs. The elements of each pair extend centrally through those of the other pairs, and for this purpose all of the prisms, with the exception of that denoted by the numeral 15, are provided with central notches, as appears from Figs. 2 to 6, inclusive. The prism 10 is provided with a notch 16, extending from one of its faces to its longitudinal center line, said notch being adapted to receive another one of the prisms of the group, as will hereinafter appear, its width corresponding to the size of one of the sides of the square base of the prism and its depth being half of its width. The prism 10 forms a pair with the prism 12. The latter being provided in one of its sides with a notch 17, adapted to receive a pair of prisms, when placed side by side. The width of this notch is twice that of the notch 16, its depth corresponding to that of the notch 16. When the prisms 10 and 12 are placed side by side with their notches in registering positions, as shown in Fig. 8 of the drawings, these notches merge one into another and form a substantially L-shaped slot.

Through this L-shaped slot is extended the prism 11 (Fig. 9), the last mentioned prism being provided with a notch 18 in one of its sides, into which merge two notches, denoted by the numerals 19 and 20, in the adjacent side of the said prism. The width of the notch 18 corresponds to that of the notch 16 and the widths of the notches 19 and 20 being each one-half of the width of the notch 18. The notches 19 and 20 are spaced apart a distance corresponding to that of the width of the notch 18. In combining the prism 11 with the prisms 10 and 12, the portion 21 of the prism 11 between the notches 19 and 20 is disposed in the L-shaped slot above referred to. When the elements are in these positions (Fig. 9), the notch 19 is disposed above the prisms 10 and 12 and the notch 20 below the same, the last mentioned notches facing the base 22 of the L-shaped slot.

The prisms 13 and 14 are extended at right angles to the prisms 10 and 12 and also to the prism 11. The prisms 13 and 14 are alike in construction, each being provided in one of its faces with a notch 23 and in the adjacent face with a notch 24. These

two notches merge one into the other, the width of each notch 23 corresponding to that of the notch 17 and the width of each notch 24 to that of the notch 16. In combining the prism 13 with the prisms 10, 11 and 12, the prisms 10 and 12 are seated in the notch 23 and then the prism 13 forced into the notch 19 in the prism 11 (Fig. 10), whereby the notch 24 in the prism 13 is brought into registering position with the base 22 of the L-shaped slot in the prism pair 10 and 12. In a similar manner is the prism 14 united with the prisms previously assembled, the elements being then in the positions shown in Fig. 11 of the drawings.

The prism 15 serves to lock together the five prisms already assembled, it being drawn in parallel relation to the prism 11 through the registering notches in the prisms 13, 10, 12 and 14.

The locking prism, that is to say the prism 15, carries a pin 25, which is forced into one of the sides of the said prism and projects beyond the prism end, as shown in Fig. 7 of the drawings. The pin is not fully embedded in the prism 15, but rises somewhat above the side into which it is sunk. When uniting the elements, the said pin forms a wedge, that is forced against the juxtaposed side of the prism 11, thereby preventing a disengagement of the elements.

The pin 25 serves also as a spindle, around which the toy may be spun in the manner of a spinning top, the prisms 11 and 15 being grasped between two fingers of the operator and the entire contrivance given a rotary motion on the pin 25 and then released.

The prism 13 is provided on two of its opposite faces with numerals, one adjacent the end of each face, as clearly shown in Figs. 40 1 and 5 of the drawings. When the toy is spun, one of these numerals will come uppermost after the force has been spent. The device is thus adapted to be used as a game of chance.

It is to be noted that the longitudinal axis of each prism pair intersects the longitudinal axes of the other pairs, when the toy is assembled (Fig. 1).

What I claim is:—

A building block toy, comprising three pairs of quadrangular prisms adapted to be interlocked, all of said prisms but one being provided with notches accommodating portions of the prisms, the members of each pair of prisms extending side by side and at right angles to the other pairs of prisms, the longitudinal axis of each prism pair intersecting the longitudinal axes of the other pairs, and a pin in the side of said notchless prism abutting against the juxtaposed face of its pair, said pin extending out of the side of the notchless prism, thereby forming a wedge to prevent accidental disengagement of said notchless prism from the remaining elements, when assembled, said pin projecting beyond one end of said notchless prism and constituting a spindle on which the assembled toy may be spun.

Signed at New York, in the county of New York and State of New York, this 15th day of March, A. D. 1921.

DAVID LEVINSON.
